UNITED STATES PATENT OFFICE

JAMES M. DIVAN, OF FREEPORT, ILLINOIS, ASSIGNOR OF ONE-HALF TO
WILLIAM NELSON, OF MONTROSE, MISSOURI.

KNOCKDOWN CRATE.

No. 810,369.

Specification of Letters Patent.

Patented Jan. 16, 1906.

Application filed June 2, 1905. Serial No. 263,408.

To all whom it may concern:

Be it known that I, JAMES M. DIVAN, a citizen of the United States of America, residing at Freeport, in the county of Stephenson and 5 State of Illinois, have invented certain new and useful Improvements in Knockdown Crates, of which the following is a specification.

My invention relates to improvements in 10 knockdown crates and is fully described and explained in this specification and shown in the accompanying drawings, in which—

Figure 1 is a perspective view of my improved crate. Fig. 2 is a section in the line 2 15 2 of Fig. 1. Fig. 3 is a perspective view of the fittings which connect the top and end section with the crate. Fig. 4 is a perspective view showing the partition-hinge. Fig. 5 is a transverse section in the line 5 5 of Fig. 20 Fig. 6 is a similar view showing the crate knocked down. Fig. 7 is a perspective view showing the manner in which the top section is locked down, one of the top sections being omitted in the drawings. Fig. 8 is a perspective view showing the sliding cover and its 25 supports, and Fig. 9 is a perspective view of the crate partly knocked down.

Referring to the drawings, A is the bottom 30 of my improved crate, and the same is provided with upwardly-projecting side boards a, the vertical height of which above the body is equal to the combined thickness of the ends and top sections of the crate. To the upper edges of the side boards a are hinged 35 sides B, preferably composed of vertical members b and horizontal slats b', and to the upper edges of these sides B are hinged top sections C, comprising transverse members c and longitudinal slats c'. It will be seen that 40 the hinges between the sides and top sections are placed within the edges of the top sections, Fig. 9, so that when the sections are swung up they will make a perfect corner for the crate.

45 The ends of my improved crate are indicated in the drawings by D, the same comprising vertical end pieces d, central pieces d', and horizontal slats d''. These ends are hinged to the bottom A of the crate and can 50 be swung down therein, as seen in Fig. 9, when they will lie below the side boards a, attached to the bottom.

E indicates a central partition which is adapted to divide the crate into two substan-

tially equal portions. This partition 55 comprises vertical end pieces e, a vertical center piece e', and horizontal slats e''. The ends of the partition are provided with laterally-projecting pins e³, which run in cam-slots e⁴ in plates e⁵, secured to the side boards a of the 60 bottom of the crate. This central partition E can be swung down to the left, as seen in Fig. 2, whereupon its lower end can be slid along the cam-slot to the end thereof, when the partition will lie flat upon the bottom of 65 the crate, a strengthening-cleat a' falling between two of the horizontal slats of the partition. I consider this horizontally-movable pivot for the central partition particularly desirable, for the reason that it enables the 70 partition to occupy the exact center of the crate, both when the crate is erected and when it is knocked down, and thus makes room on the bottom for the end pieces, while also serving to divide the crate into two equal 75 compartments.

The general operation of the device will be readily apparent. Starting with the device, as in Fig. 1, if it is desired to knock down the 80 crate the end pieces are first pushed in, as shown in Fig. 9, and the central partition folded down. Thereupon the two top sections of the crate can be swung down against the adjacent sides thereof, and the sides can be folded down, as shown in Fig. 6. It will 85 be seen that the ends and center partition and also the top sections of the crate lie below the hinge-line of the sides thereof on the bottom.

Having described the general structure of 90 my device and its mode of operation, broadly considered, I shall explain certain more specific features, which are especially desirable. In the first place, it is desirable that some means be provided for locking the members 95 of the crate together when it is in its opened position. For this purpose I provide the free corners of the top sections with hooks C', of sheet metal, Fig. 3, and I place on the upper edge of the ends of the crate sheet-metal 100 fittings D', having hooks at their opposite ends arranged to engage with the adjacent hooks C'. It will be seen that when the crate is erected these hooks can be interlocked, and the crate will be given a very substantial 105 structure not liable to accidental derangement.

In order to lock the portions of the crate

together when the crate is knocked down, I provide a sheet-metal yoke E' on the central partition E and place upon the upper end of this yoke a rotatable button E², adapted to engage the inner edges of the top sections of the crate to hold the same down.

In order to give access to the two ends of the crate, I cut away one of the slats in one of the top sections at each end of the crate, Figs.

- 10 1 and 9, and place under the slats a horizontally-slidable board C², guided in small channeled guide-strips c² on the transverse members of the top sections. This sliding door can be locked either in an open or closed position by means of a small spring C³, engaging with depressions therein.

I realize that considerable variation is possible in the details of this construction without departing from the spirit of my invention, and I do not, therefore, intend to limit myself to the specific form herein shown and described.

I claim as new and desire to secure by Letters Patent—

- 25 1. In a device of the class described, the combination with a suitable bottom, foldable sides and top sections, of foldable end sections hinged to the ends of the bottom and arranged to swing down upon the same, and
- 30 3. a central partition having a movable pivot connection with the bottom, whereby it can be erected at the center of the bottom, or folded down at the center of the same.

- 35 2. In a device of the class described, the combination with a suitable bottom, foldable sides and top sections, of foldable end sections hinged to the ends of the bottom and arranged to swing down upon the same, a central partition, projecting pins at the lower

corners thereof, plates having slots supported 40 by the bottom with which the pins engage, said slots extending substantially from the center of the bottom toward one end thereof, a distance equal to substantially half the height of the partition, whereby the partition 45 can be erected at the center of the bottom, with the pins at one end of the slot, or folded down on the center of the bottom with the pins at the other ends of the slots.

3. In a device of the class described, the 50 combination with a bottom, ends hinged at the ends thereof, sides hinged at the edges thereof and top sections hinged to the sides, of hooks at the free corners of the top sections, and corresponding hooks arranged in 55 pairs at the centers of the tops of the ends, said hooks being constructed and arranged to engage mutually to hold the crate in its erected position.

4. In a device of the class described, the 60 combination with a bottom, sides hinged thereto, top sections hinged to the side sections, and ends hinged to the ends of the bottom, of a partition pivoted to the bottom and arranged to swing down at the center thereof, 65 an upward projection on said partition and a rotatable button on said projection arranged to engage with the adjacent edges of the top sections to lock the crate in a closed position.

In witness whereof I have signed the above 70 application for Letters Patent, at Freeport, in the county of Stephenson and State of Illinois, this 25th day of May, A. D. 1905.

JAMES M. DIVAN.
